UNITED STATES PATENT OFFICE.

JOHN C. HARRINGTON, OF PROVIDENCE, RHODE ISLAND.

BRACELET.

SPECIFICATION forming part of Letters Patent No. 267,886, dated November 21, 1882.

Application filed August 7, 1882. (No model.)

To all whom it may concern:

Be it known that I, JOHN C. HARRINGTON, of Providence, in the State of Rhode Island, have invented an Improvement in Bracelets, 5 of which the following is a specification.

My invention relates to an improvement in that class of bracelets which are formed of openly-coiled wire, and are secured to the wrist by bringing the ends of the bracelet laterally nearer to each other and connecting them in 10 that position by means of a hook; and it consists in the combination of a hook-stud attached to one of the lapped ends of the bracelet, with an ornamental catch provided with a perforated back plate and hinged to the opposite 15 arm of the bracelet.

Figure 1 represents a side elevation of the bracelet. Fig. 2 is a top view of the same. Fig. 3 is a section taken in the line *xx* of Fig. 2. Fig. 4 represents the bracelet opened for the insertion of the wrist.

In the drawings, A is the coiled wire of the bracelet, and is preferably made hollow, as shown in the section, Fig. 3, and provided at 25 its ends with the knobs *a a*. To one of the lapped ends of the coil, at the intermediate point between the two knobs *a a*, is secured the hook-stud B, and at the same point on the

opposite lapped end of the wire is secured the ornamented catch C, by means of the hinge D, 3c and in the back plate of the catch C is made a slot, F, adapted to receive the hook-stud B, which is so formed or bent as to operate, in conjunction with the spring action of the wire A, which tends to the lateral separation of the 35 lapped ends, to properly hold the bracelet upon the wrist of the wearer, the position of the several parts of the bracelet in this case being shown in Figs. 1, 2, and 3, and the open position assumed by the wire A upon releasing the catch C is shown in Fig. 4.

I claim as my invention—

In a bracelet, the combination of the laterally-open coil of wire A, made in bracelet form, with laterally-lapped ends, the hook-stud B, attached to one of the lapped ends of the bracelet, and the ornamental catch C, hinged to the opposite arm of the bracelet, and provided with a back plate having a slot, F, adapted for the reception of the hook-stud B, substantially as 45 50 described.

JOHN C. HARRINGTON.
